I claim the ornamental design for an apple paring machine frame, as shown and described.

DESCRIPTION

FIG. 1 is a top perspective view of an apple paring machine frame, showing my new design.

FIG. 2 is a front elevational view of the apple paring machine frame.

FIG. 3 is a rear elevational view of the apple paring machine frame.

FIG. 4 is a left side elevational view of the apple paring machine frame.

FIG. 5 is a right side elevational view of the apple paring machine frame.

FIG. 6 is a top plan view of the apple paring machine frame; and,

FIG. 7 is a bottom plan view of the apple paring machine frame.

The broken lines are for the purpose of illustrating portions of the apple paring machine frame forming no part of the claimed design.
